INSULATED RECORD CONTAINER

Edwin H. Mosler, New York, N. Y., and Harry H. Lynn, Wyoming, Ohio, assignors to The Mosler Safe Company, Hamilton, Ohio, a corporation of New York

Original application January 5, 1940, Serial No. 312,578, now Patent No. 2,347,705, dated May 2, 1944. Divided and this application December 26, 1940, Serial No. 371,628

11 Claims. (Cl. 109—74)

This application is a division of our pending application entitled Insulated record container, bearing Serial Number 312,578 and filing date of January 5, 1940 and issued May 2, 1944 as Patent No. 2,347,705.

This invention relates to an insulated record cabinet or container or safe which is adapted to withstand high temperatures, crushing forces, and other destructive actions incidental to accidental fire and like disasters.

An object of the invention is to provide a cabinet of the kind mentioned above, which includes structural advances that render the cabinet highly protective of its contents, under conditions which would ordinarily melt, distort, mangle or explode other cabinets of the same general type.

Another object is to avoid having to laboriously manipulate heavy insulated drawers, in a record cabinet designed for the protection of its contents from fire or intense heat.

Another object of the invention is to provide an improved closure for insulated record cabinets, which is highly resistant to entry of directed water, heat, flame, dirt and dust, and which is further characterized by an outstanding ability to prevent explosion of the cabinet in the presence of extremely high temperatures.

Another object is to provide a cabinet and closure arrangement that will withstand the crushing effect of dropping the cabinet bodily, when closed, through a distance approximating thirty feet, as sometimes occurs in the collapse of a fired building or its flooring.

A further object of the invention is to provide an improved bolt-work for safes and cabinets, and like depositories.

An object also, is the accomplishment of the above objects and advantages inexpensively, and with the greatest possible degree of efficiency.

The foregoing and other objects are attained by the means described herein and disclosed in the accompanying drawings, in which:

Fig. 1 is a front elevational view of an insulated record cabinet of the invention, showing the door 7 thereof in the normal open, yet concealed, position at one side of the cabinet.

Fig. 2 is a cross-sectional view taken horizontally through the cabinet of Fig. 1, but with the door in the closed and bolted condition.

Fig. 3 is an enlarged fragmental cross-sectional view taken through the cabinet door, on line 3—3 of Fig. 4, the insulating material being removed.

Fig. 4 is a rear elevational view of the improved

door and bolt-work embodying the present invention.

The cabinet of this invention is so constructed as to perform the services of an ordinary record filing cabinet having sliding drawers disposed vertically, but embodying also a reinforced and insulated construction in furtherance of the objects stated above. This improved construction embodies also a disappearing door 7, which may enter an auxiliary vertical compartment 8 at one side of the cabinet, when opened. The disappearing feature of the door will not receive detailed treatment in this description, since it is possible to accomplish that in various ways, an example of which is disclosed in the prior art patent of Abbott et al. No. 1,873,247, granted Aug. 23, 1932. Unlike the device of the patent just mentioned, the device of the present invention is devoted more to the problem of preserving the contents thereof, than to that of resisting burglary or forced entry to the contents. Accordingly, various structural difference will necessarily prevail, for distinguishing the devices one from the other.

Referring to sheet 1 of the accompanying drawings, 9 indicates the top, 10 the bottom, and 11 and 12, the side walls, of an outer shell constituting the cabinet exterior. The cabinet may be placed upon a base 13, if desired. The top and bottom walls preferably are extended as at 14 and 15, to one side of the cabinet, where they are joined by an exterior wall 16 to form the auxiliary compartment 8 that houses the disappearing door 7 when the door is open, as illustrated in Fig. 1.

Within the auxiliary compartment, there may be provided one or more horizontal tracks 17 adapted to support a wheeled carriage 18 that carries the hinge leaves 19 of the door 7. An extension 20 of the door, which substantially closes the front of the auxiliary compartment normally, carries the other hinge leaf 21, the leaves being joined pivotally by means of a hinge pin 22, as will be understood. Upon opening the door of the cabinet, the door may be positioned in substantial parallelism with the carriage 18, so that the carriage may be rolled rearwardly upon the track 17 carrying with it the door 7 so that the door will be housed substantially within the auxiliary compartment 8 in substantial parallelism with the walls 12 and 16 of the cabinet. The characters 23 indicate rollers on carriage 18, to facilitate shifting of the carriage as stated. A corner reinforcement 24 may be provided for the auxiliary compartment, at both

the front and the rear thereof, if necessary or desirable. As previously stated herein, the details of the carriage are relatively immaterial to the present invention, wherefore a detailed description is deemed unnecessary.

The cabinet proper is lined with an inner shell which is substantially smaller than the outer shell, so that suitable insulating material 25 may be impacted between the shells to protect the contents of the cabinet from intense heat and flame, when required to meet such conditions. The inner shell comprises side walls 26, a bottom wall 27, a top wall 28, and a rear wall 29 which extends substantially the full height of the cabinet. The inner shell may be constructed of light gauge metal, however, it is to be reinforced so as to resist possible crushing and serious distortion in the event that the cabinet be dropped a substantial distance, such as might occur in the event that a floor collapses or becomes weakened by reason of destruction of other parts of a building. The reinforcement consists in providing a series of sheet metal shelves or partitions 30, each extending from the rear wall of the cabinet inner shell to a location near the front of the cabinet. The forward edge 31 of each shelf preferably is reinforced by turning it at right angles to the body of the shelf, thereby providing flanges such as 31. The shelves are securely fixed along their side and rear edges to the inner shell of the cabinet, preferably by means of welding, so that the inner shell with its shelves or partitions, constitutes an integral rigid unit. The characters 6 of Fig. 2 indicate fusible plugs in the door and outer walls for the release of gases generated along such walls when subjected to high temperatures.

In constructing the cabinet interior, it is found desirable to terminate the forward edges 33, of the inner shell side, top and bottom walls to a location remote from the front of the cabinet, and to furnish side, top and bottom door jamb inserts, indicated at 34, to complete the forward portion of the inner shell. These inserts preferably overlap the inner shell walls as at 35, and are spot welded thereto at spaced intervals thereby establishing the desired rigidity. Since the welds are at spaced intervals, the shell walls and the inserts will not be in intimate contact except at a few points, wherefore there is established at the overlap a heat conductivity break or interruption between the exterior and the interior of the cabinet, for protecting the contents. It will be noted that the jamb inserts are flared outwardly at 35 and then projected inwardly as at 36, to furnish bolt keeper recesses or channels 37 for accommodating the door bolts. The channels or recesses are continuous about the entry port or doorway of the cabinet. Forwardly of the channel or recess of each jamb insert, the metal is projected on a slight angle to provide the sloping or tapered jamb face 38 which accommodates the complementary jamb face 39 of the door 1. At the extreme forward edge of face 38, the insert is turned upon itself as at 40 to enter a channel 41 of the outer shell. Within the channel 41, which extends circumferentially of the doorway, the flange 40 of the jamb insert is welded at intervals to the metal of the jamb, thereby further establishing the desirable rigid and integral nature of the cabinet parts while at the same time providing for the relief of any gases generated within the filling material 25 under high temperature conditions.

At this point in the description, attention may be directed to the fact that the various compartments formed between the shelves 30 and the top and bottom walls of the inner shell, are adapted to receive filing drawers or other containers to which access may be desired when the cabinet door is opened. Such drawers or containers have been omitted from the drawing disclosures in the interest of clarity, and for the further reason that the cabinet need not necessarily be provided with such fixtures.

In furtherance of some of the objects of this invention, the door of the cabinet is of special design, and comprises a rather substantial front plate or panel 42, of which the side extension 20 preferably is an integral part. Along the top, bottom, and one side edge thereof, the door may be flanged as at 43, these flanges being adapted for reception in the continuous channel 41 which bounds or defines the doorway of the cabinet. Another flange 44 for the same purpose, may be provided on a separate upright plate 45 which is welded or otherwise permanently fixed to the inner face of panel 42, the separate plate being used also as a reinforcement where the hinge leaf 21 is fixed to the door. Plate 45 may be flanged also at 46, to strengthen the door structure and to also act as a stop limiting the movement of the door about this hinge connection to the carriage 18.

As clearly illustrated in Fig. 2, a suitable recess 47 may be provided in the front plate of the door, for the reception of a manipulating means for the bolts of the door, which manipulating means is in the present embodiment constituted of a handle 48 pivoted as at 49 upon a cross-piece 50 of the bolt actuating shaft or spindle 51. The purpose of providing the recess, and of pivotally mounting the handle at 49, is to enable the handle to be displaced to a position flush with the front of the door when the handle is not in use, thereby to eliminate possible interference with disposing the door to the inoperative and substantially concealed position illustrated in Fig. 1.

The character 32 indicates any acceptable type of lock for the boltwork.

Within the limits of the space defined by flange 44, and the upper, lower, and edge flanges 43, the inner face of the door front or plate 42 supports the securing flanges 52 of the metallic strips 53 that furnish the door jamb areas 39. These strips extend along the top, bottom, and side edges of the door proper, within the limits established by the four flanges indicated at 43 and 44, and may be formed either in separate horizontal and vertical sections, or integrally as a single strip. Fixation of the strips through the agency of their respective flanges 52, to the inner face of the door panel 42, may be by way of welding or otherwise, as desired.

The free edge 54 of each strip 53 is turned inwardly toward the center of the door, at a distance from the front panel 42, providing a compartment 55 behind the major portion of the door panel, which compartment is adapted to be packed with insulating material 56 of any acceptable kind. The flanges function also as the primary supporting means for the bolt-work with which the door is equipped. In the form of the invention illustrated, the two upright flanges 54 of the door are spanned at intervals by a series of substantial plate-like struts indicated by the characters 57, 58, and 59, the opposite ends of which struts are welded or otherwise perma-

nently attached to the said upright flanges 54. In addition to supporting the bolt-work and reinforcing the door structure, the plate-like struts serve also to hold the insulating material 56 in position within the internal structure of the door.

The inner finish panel or sheet 60 may aid also the functions mentioned, in addition to imparting a finished appearance to the inside of the door. This element 60 has been removed from the Fig. 4 illustration and is shown by means of broken lines in Fig. 3, in order to most clearly expose the bolt-work and the back of the door.

The door bolts herein disclosed are not of the customary variety, but are formed from elongated steel plates following somewhat the teaching disclosed in the patent of W. Corliss No. 447,488, dated March 3, 1891. In a very general way the Corliss patent discloses the type of bolt plates employed herein. The bolt plates herein are identified by the reference characters 61 and 62 for the vertical bolt plates, and by the characters 63 and 64 for the horizontal plates. The several bolt plates are arranged for sliding movement to extended and retracted positions, all of them moving outwardly or inwardly in unison when the primary link shifter 65 is rotated by means of the handle 48 located exteriorly of the door. The opposite ends of each bolt plate are mitered, as indicated generally at 66, preferably at an angle approximating 45°. When the bolt plates are fully retracted, as illustrated in Fig. 4, the mitered ends thereof abut, or preferably so.

The three door bolts indicated at 61, 62, and 63 may be mounted for shiftability relative to the inturned flanges 54 of the strips 53 in any acceptable manner, such as by providing them with elongated slots 67 through which extend the studs 68 which are anchored to the several flanges 54. Such studs are most clearly illustrated in Fig. 3, and are seen to include a thread end 69, the threads of which engage the internally threaded bore 70 of a reinforcing metallic bar 71 which backs the circumferential flange assembly 54. In other words, reinforcing bars such as 71 function as thread nuts into which the screw thread ends of the various bolt plate mounting studs may engage, for anchoring the studs to the door. The characters 72 and 73 indicate, respectively, a spacing washer and a screw adapted for mounting the finish panel or sheet 60 upon the rear of the door. As shown in Fig. 3, the screw 73 may enter a central threaded bore 74 of the mounting stud 68. All of the mounting studs may be utilized in this manner to support the finish panel, if desired.

Attention is now directed to the means shown in Fig. 4 for shifting the bolt plates upon rotation of the handle 48 and its spindle 51. The primary link shifter 65 conveniently may be formed from a flat plate centrally mounted in fixed relationship to the operating spindle 51. The end of the spindle that supports the plate may be squared or provided with one or more flats, so that the plate may not rotate relative to the spindle. Pivots 75 on the plate or shifter 65, serve to mount the inner ends 76 and 77 of a pair of T-links 78 and 79 at opposite sides of the spindle 51, whereby rotation of the spindle and its associated shifter plate will result in longitudinal reciprocation of the T-links in unison. The head-bar 80 of T-link 78 has its opposite ends perforated as at 81 and 82 for the reception of the turned lugs 83 on each of the secondary

shifters 84 and 85. By this means, the vertical shifting of T-link 78 results in rotational movement of the secondary shifters about their respective pivots 86. At the locations 87 and 88 of each of said secondary shifters, a connection similar to 81-83 is provided, for shifting longitudinally the pairs of links 89-89 and 90-90. The links 89 serve to elevate and lower the upper horizontal bolt plate 63 when the bolt-work is actuated, and in like manner the pair of links 90-90 operate upon the vertical bolt plates 61 and 62 for shifting them bodily to extended and retracted positions simultaneously with movement of the bolt plate 63.

At the lower portion of Fig. 4, the head-bar 91 acts in precisely the manner above referred to, to rotate the secondary shifters 92 and 93 for reciprocating the pairs of links 94-94 and 95-95. By means of these link pairs, the lower ends of the bolt plates 61 and 62, and the lower horizontal bolt plate 64, are adapted to be moved in unison with the bolt structures at the upper end of Fig. 4.

From all of the foregoing, it will be understood by reference to Fig. 2, that rotation of the main spindle 51 by means of handle 48, will result in extending all of the bolt plates to the outward limit of travel so that each bolt plate will engage its cooperative channel or groove 37, and since the channels or grooves are joined at their ends to form a continuous recess within the doorway of the cabinet, a rather effective seal will be established when the door is closed and bolted. This seal in combination with an insulated door and an insulated cabinet, is most desirable and constitutes an advance in cabinet structures of the insulated type. The reason for this is that any insulating material when subjected to high temperatures will liberate gases, thereby generating high pressures within the cabinet capable of bursting the cabinet if confined too securely, or of igniting and possibly damaging the contents of the cabinet if the gases are liberated too freely from the cabinet interior. By this is meant, that the metal of the cabinet or its closure, when subjected to high temperatures, will promote the liberation of hydrogen gas from the insulating material, and since this gas is of a combustible nature it should be liberated from the cabinet as a slight seepage, rather than freely, in order to minimize the possibility of ignition and explosion within the confines of the cabinet. The type of seal effected by the bolting means of this invention safeguards the cabinet against the hazards mentioned. The insulating material within the door and between the inner and outer shells of the cabinet serves to effectively protect the contents of the cabinet from damage by fire or extreme heat to which the device may be subjected during a conflagration. The door bolting means, being semi-tight to the extent necessary for precluding ignition and explosion of liberated gases within the cabinet is nevertheless sufficiently tight to prevent directed water and other foreign substance from entering the cabinet under the adverse conditions accompanying and incidental to a conflagration.

It sometimes occurs that a floor or other support upon which the cabinet is standing, will collapse and allow the cabinet to plunge for a distance approximating the height of a building story, and under such circumstances it may generally be expected that the cabinet will land with its bottom foremost upon the floor below. The impact resulting from such a plunge will ordi-

narily be directed against the lower horizontal bolt plate 64, and if the force is sufficient to move that particular bolt plate to the retracted position, the remaining bolt plates would be actuated through the links 95 and all of the other links, to similarly retract each of the bolt plates, thereby leaving the door free to swing open and expose the contents of the cabinet to destruction. To guard against this possibility, the lower horizontal bolt plate 64 is provided with a special type of connection with the bolt-work link structure.

With reference to Fig. 3 and the lower half of Fig. 4, it will be noted that links 95 have their upper ends 97 pivoted at 96 upon the turned lugs of the secondary bolt shifters 92 and 93, whereas the lower ends of said links have their studs 98 received in the elongated slots 99 of the bolt plate 64. Accordingly, it might be expected that by restraining the bolt plate 64 against downward shiftability, the bolt-work could be actuated to move the links 95 downwardly without moving the bolt plate, the studs 98 traveling freely in the slots 99. But such action does not normally occur, due to the interposition of springs 100, each of which has an upper end 101 abutting a link 95 or an extension 102 thereof while the opposite end 103 of the spring bears upon, or is fixed to, the bolt plate 64. From this it will be understood that downward movement of the links 95 is transferred to the bolt plate 64 through the springs 100, so that under normal conditions the bolt plate will move with the links, without any perceptible movement differential. However, in the event that a sharp blow is applied upwardly against the bolt plate 65 while the bolt is extended, the springs 100 will absorb the shock of the blow before the force thereof may be transmitted to the links 95 to undesirably actuate the entire bolt-work assembly. The relationship of the spring to the link and the bolt plate, is very clearly illustrated by Fig. 3. As shown therein, the lower end 103 of the spring is anchored in an aperture 104 provided in a shoulder 105 that extends the full length of the bolt plate 64. Like all of the other bolt plates, the lower bolt plate 64 is guided in its upward and downward movements by means of the stud and slot arrangement indicated at 67—68. A reinforcing bar 71 together with flange 54 furnishes the necessary mounting means for the studs 68 which enter the elongated slot 67 for guiding the horizontal bolt plate 64 in its movement toward and from the extended and retracted positions.

From the foregoing it should be understood that the cabinet of this invention when subjected to a sharp impact from below, at any time that the bolts are extended as in Fig. 2, will be safeguarded against accidental retraction of all its bolt plates, by reason of the resilient connection between the bolt plate 64 and its associated linkage. The intervention of springs 100 under normal circumstances does not interfere with the extension and retraction of bolt plate 64 simultaneously with the remaining bolt plates. The safety linkage becomes operative only in the emergency heretofore mentioned. It may be noted that the links other than those at 95, have regulation pivotal connections 105 with their respective bolt plates, no lost-motion connection being there required; however, the bolt-work obviously would operate satisfactorily if two or more of the bolt plates were equipped with resilient lost-motion connections illustrated and explained with reference to bolt plate 64.

Referring now to the extreme left ends of the horizontal bolt plates 63 and 64, it will be noted that their outer edges 107 and 108, respectively, are provided with rather long inclines or tapers beginning at the points A and extending to the miter of each bolt plate end. These tapers or inclines it will be noted, are located adjacent to the hinge region of the door, and their function is to perform as cams to engage the forward portion of the upper and lower jamb areas of the doorway for automatically retracting all of the door bolts, in the event that the door inadvertently is moved toward the closed position with the bolts extended. As will be understood, serious damage might result from an attempt to close the door while the bolts are extended, unless some means were provided for automatically retracting the bolts. With reference to Fig. 1, it may be observed that the inclines or cam surfaces 107 and 108 will engage the doorway of the cabinet at approximately the locations B and C, respectively, should the bolts be extended while the door is moved toward the closed position, whereupon a camming action will occur causing the upper and lower bolt plates to be forced inwardly to their retracted positions. The vertical bolt plates, of course, will likewise retract due to their connection with the bolt-work, as the latter will necessarily be actuated automatically upon forceful retraction of bolt plate 63, for example. Under the circumstances referred to, it will not be necessary for anyone to manipulate the handle 48.

A cabinet structure of the character herein illustrated and described possesses many advantages not heretofore embodied in devices presently known and used. The improved structure is not unduly heavy, and it may therefore be moved about in much the same manner as an ordinary or commonly known file cabinet; yet it furnishes a high degree of protection against internal explosion or destruction of its contents in the event of fire, water and building collapse. The constituents of the improved cabinet are simple and inexpensive, and are not likely to become out of order, so that maintenance costs are low and any necessary repairs may be accomplished inexpensively without returning the cabinet to the factory or other service station. The automatic safety features with which the device is equipped enables it to withstand abuses which would in other cabinet structures result in springing the hinges, the door or the cabinet proper, or otherwise inflicting serious damage upon the assembly.

As hereinbefore stated, injury to the cabinet by possible explosion, or destruction of the contents by accidental release of the door bolts resulting from impact, are effectively reduced to a practical minimum in the improved structure of this invention. It is of importance to note that the peripheral closure formed by the four door flanges 43 and 44 serves, in the closed position of the door, to lock the door and the cabinet body together so as to add structural strength to the combination for opposing any forces tending to crush or distort it. The long side walls of the cabinet are thereby reinforced against bulging or buckling during a drop, or upon exposure to fire or heat. The flange lock between the door and cabinet also has the effect of obstructing access of atmospheric oxygen to the jamb space along the door edges in the event that the jamb space becomes filled with combustible gases from the cabinet interior. Accordingly, any combustible gases liberated from

the jamb space will have an opportunity to reach the cabinet exterior along the outer edges of the door, where combustion thereof will be harmless and reduced in force because the gas will there be unconfined. The elongated door bolts, being along the extreme inner edges of the door, perform as flame arresters against any small explosions that might possibly backfire into the jamb spaces, although this possibility is reduced to a practical minimum by the flangess 43-44. The elongated door bolts and the flanges 43-44, therefore, will be seen to inject an unusually high factor of safety, as coordinated herein, protective of the cabinet contents to an extent heretofore unattained. Other advantages and objects of more or less importance are mentioned in other passages of this description.

It is to be understood that various modifications and changes in the structural details of the device may be made, within the scope of the appended claims, without departing from the spirit of the invention.

What is claimed is:

1. A cabinet of the class described, which comprises an outer shell having top, bottom, rear, and side walls, an inner shell likewise having top, bottom, rear and side walls, said inner shell walls being of reduced proportions such that the inner shell fits within the outer shell with the walls of one shell spaced from the corresponding walls of the other shell, said shells having corresponding forward marginal edges spaced apart near the front of the cabinet, a series of door jamb inserts each adapted to join a wall of the inner shell to a corresponding wall of the outer shell at the cabinet front, said inserts each overlapping a margin of the inner shell and comprising a longitudinal door bolt keeper channel and an adjacent sloping jamb face, the channels all being fitted to form a single circumferential inner recess near the cabinet front, with the inserts welded at intervals to both shells for rigidity and resistance to deformation, insulating material of limited compressibility between the shells, and a multiplicity of reinforced shell-spanning shelves having edge portions horizontally disposed and welded to the overlapping area of the inner shell and the jamb inserts, to form therewith a unitary rigid inner structure highly resistant to crushing forces imposed upon the outer shell and transmitted to the inner shell through the insulating material.

2. A cabinet of the class described, which comprises an outer shell having top, bottom, rear, and side walls, an inner shell likewise having top, bottom, rear and side walls, said walls being of reduced proportions such that the inner shell fits within the outer shell with the walls of one shell spaced from the corresponding walls of the other shell, the forward edges of the inner shell terminating at a substantial distance from the front of the cabinet, a multiplicity of reinforced shell-spanning shelves having front edges terminating near the forward edges of the inner shell, and including marginal portions welded to the inner shell and forming therewith an integral unitary inner structure highly resistant to crushing forces imposed upon the outer shell, a series of door jamb inserts along the top, bottom, and side walls of both shells, and placed end to end for providing a continuous door jamb, said inserts being connected to the inner shell only at spaced intervals remote from the jamb areas of the inserts, thereby to establish a heat conductivity break at the inner shell for interrupt-

ing the passage of heat from the exterior of the cabinet to the interior thereof at a series of locations removed from the jamb areas.

3. A cabinet of the class described, which comprises an outer shell having top, bottom, rear, and side walls, an inner shell likewise having top, bottom, rear and side walls, said walls being of reduced proportions such that the inner shell fits within the outer shell with the walls of one shell spaced from the corresponding walls of the other shell to receive insulating material, an insulated door hinged for closing upon the inner shell to seal it against ingress and egress of foreign matter, a series of door jamb inserts along the top, bottom, and side walls of both shells, and placed end to end for providing a continuous door jamb, said inserts being connected to the inner shell only at spaced intervals, thereby to establish a heat conductivity break at the inner shell for interrupting the passage of heat from the exterior of the cabinet to the interior thereof, a circumferential exterior channel formed integrally with the outer shell and bounding the continuous door jamb, and a cooperative continuous flange on the door for entry into said channel when the door is closed, to lock the door and cabinet together and preclude side wall bulge and distortion during a drop or exposure of the cabinet to exteriorly applied heat.
4. A cabinet of the class described, which comprises an outer shell having top, bottom, rear and side walls, and a forward continuous door flange channel constituted of grooves formed in all but the rear wall, an inner shell including walls corresponding to those of the outer shell, the inner shell being of reduced size to fit within the outer shell leaving spaces between the corresponding shell walls for insulating material, a door jamb insert of open frame construction fitted to the top, bottom, and side walls of the inner shell, but out of intimate full contact with the walls of the inner shell so as to provide a heat conductivity break between the exterior and the interior of the cabinet, and a succession of spaced welds within the confines of the forward channel for anchoring the door jamb insert to the outer shell walls.
5. An insulated record container which comprises in combination, an outer shell having top, bottom, rear and side walls, an inner shell including walls corresponding to those of the outer shell, the inner shell being of reduced size to fit within the outer shell leaving spaces between the corresponding shell walls containing insulating material, and a door jamb insert of open frame construction fitted to the top, bottom, and side walls of both shells, but out of intimate full contact with the walls of the inner shell so as to provide a heat conductivity break between the exterior and the interior of the cabinet.
6. An insulated record container which comprises in combination, an outer shell having top, bottom, rear and side walls, an inner shell including walls corresponding to those of the outer shell, the inner shell being of reduced size to fit within the outer shell leaving spaces between the corresponding shell walls, a door jamb insert of open frame construction fitted to the top, bottom, and side walls of the inner shell, but out of intimate full contact with the walls of the inner shell, so as to provide a heat conductivity break and a gas pressure relieving space between the exterior and the interior of the cabinet, a door for the record container, and means associated with said door and the jamb insert performing

as a diffusing means preventing the formation of a localized explosive mixture of gases at the jamb when the door is closed.

7. A cabinet of the class described, which comprises an inner shell and an outer shell insulated from one another and providing an access opening for the cabinet, a peripheral groove and a corner formed integrally on the outer shell to define the access opening, a door jamb insert connecting the shells at said opening, said insert being channeled circumferentially to provide a door bolt keeper continuous with the opening, to accommodate a door flange adapted to enter the peripheral groove of the outer shell, and means securing a circumferential edge of the insert to the outer shell at a plurality of locations within the bolt keeper groove of the outer shell of the cabinet, leaving portions unsecured for the release of gases from the space between the shells.

8. A cabinet of the class described, which comprises an outer shell having top, bottom, rear and side walls, and a forward continuous door flange channel constituted of grooves formed in all but the rear wall, an inner shell including walls corresponding to those of the outer shell, the inner shell being of reduced size to fit within the outer shell leaving spaces between the corresponding shell walls to receive insulating material, and a door jamb insert of open frame construction fitted to the top, bottom and side walls of the inner shell out of intimate full contact with the walls of the inner shell so as to provide a heat conductivity break between the exterior and the interior of the cabinet, a series of spaced welds within the confines of the forward channel for anchoring the door jamb insert to the outer shell walls, a door for the cabinet including a jamb complementary to the door jamb insert of the cabinet, elongated shiftable bolts on the door for effecting a substantially continuous seal interiorly of the door jamb insert when the door is closed and bolted, and flange means on the door for entering the forward channel and concealing the anchoring means therein, thereby substantially sealing the door jamb insert exteriorly of the cabinet in the closed condition of the door and acting as a diffuser preventing the formation of a localized explosive mixture of gases at the jamb when the door is closed.

9. An insulated record container of the class described, which comprises an outer shell having top, bottom, rear and side walls, an inner shell including walls corresponding to those of the outer shell, the inner shell being of reduced size to fit bodily within the outer shell leaving spaces between the corresponding shell walls and providing an access aperture at the front of the record container, insulating material of limited compressibility in the spaces between said shell walls, a pair of continuous channels arranged substantially at right angles to one another and bounding the access opening, an insulated door for closing the access opening, and including flange and extensible bolt means to enter said channels substantially at right angles to clutch and grip the inner shell walls at the channels whenever the bolt means are extended, and a series of horizontal rigid shell-spanning shelves welded to the opposite side walls of the inner shell to provide compartments for uninsulated light-weight file drawers to be fire protected normally by the insulated door, said shelves forming with the inner shell a unitary braced structure

highly resistant to crushing forces imposed upon the outer shell and transmitted to the inner shell through the partially compressible insulating material.

- 5 10. An insulated record container of the class described, which comprises a rectangular outer shell and an inner shell each having a forward portion defining a front opening of the cabinet, the forward portion of the outer shell all around the opening being turned inwardly and shaped to provide a continuous channel exposed toward the front of the cabinet to receive a door flange, a rectangular insert frame providing a door jamb, and comprising an inner portion fixed to the inner shell at intervals, leaving intervening areas of the insert frame out of intimate full contact with the walls of the inner shell so as to provide a heat conductivity break therebetween, a forward portion on the insert frame providing a door jamb area, and an adjacent out-turned flange to seat within the channel of the outer shell, said flange being fixed within the channel at intervals to likewise provide a heat conductivity break at the channel, and an inner continuous bolt channel in said insert frame intermediate the door jamb area and the heat conductivity break first mentioned, said bolt channel having a mouth substantially at right angles to the mouth of the first mentioned channel, and a door movable toward and from the cabinet opening, and having a jamb area, a rearwardly turned circumferential flange to enter the outer shell channel, and a series of bolt plates projectable in the plane of the door into and from the bolt channel of the insert frame, said bolts and the circumferential flange of the door serving to confine the jamb areas sufficiently to preclude localized accumulation of explosive gases within the jamb area, while effecting a diffused release of accumulated gases around the door forwardly of the door flange.
